UNITED STATES PATENT OFFICE

JOSEPH L. ORTNER, OF BUFFALO, NEW YORK

CAR BUFFER MECHANISM

Application filed April 23, 1930. Serial No. 446,452.

This invention refers to railway car buffers and platforms, more particularly of the special class consisting of vestibuled or enclosed platforms for passenger cars, the abutting vertical edges of the frames of which vestibules are equipped with a bellows-like arrangement to insure a yielding contact. The leading object of my invention is to diminish noise such as clanking and rattling in the operation of the buffer mechanism, besides making the joints closer at all times between the parts of the platform and other appliances which enter into the combination.

And the invention also comprises numerous details and peculiarities in the construction, combination, and arrangement of parts, in order to bring about the results in view, substantially as will be hereinafter described and more particularly pointed out in the ensuing clauses of claim.

In the annexed drawings illustrating my invention:

Figure 1 is a top plan view of my improved noiseless railway car buffer, the same being shown as practically applied at the abutting ends of two cars, with only a part of the car structure being shown, and many parts being indicated in outlines or in dotted line.

Figure 2 is a vertical longitudinal section of the same, taken on the line 2, 2, of Figure 1, with certain parts that are shown in Figure 1, or additional parts, being shown in side or edge view.

Figure 3 is a front elevation in detail of one of the rectangular vertical vestibule frames formed with a smooth ball-bearing, furnished surface which adapts it to easily meet a similar surface on another frame.

Figure 4 is a sectional detail view of one of the ball bearing devices in the vestibule frames.

Figure 5 is a vertical cross-sectional elevation on the line 5, 5, of Figure 2.

Figure 6 is a sectional detail of the ball bearing at the end of the buffer center stems below the car platforms.

Figure 7 is a sectional detail view of the ball bearing device on the endwise movable bars.

Like characters of reference denote like parts throughout all the different figures of the drawings.

1, 1, denotes two narrow transverse horizontal plates at the front ends of two cars, as I have indicated. These plates 1 have a rounding front edge as is usual and they are carried on certain platforms proper, as 34, which are only shown in general outline as being mounted or related, on or to, suitable end sills 25, longitudinal sills 27, castings 33 and other parts of the car construction, which are not fully shown or described here, but are represented only in sufficient detail to enable me to faithfully describe the relative location and connection of the buffer parts that constitute the essence of the invention, an essential feature of which is the resilient mounting of certain plates 2 which lie under the platform plates 1, a plate 2 being under each plate 1, and the edges of the plates 2 being normally in contact with each other as shown in Figure 2 when the cars are coupled together, but which plates separate more or less at their edges and adjust themselves vertically and otherwise during the running of the cars and especially in rounding curves and on irregular roadbeds.

The present improvements refer more especially to the means for yieldingly and adjustably supporting these metal plates 2 in a horizontal position so that they may hug tightly beneath the platform plates 1, 1, and successfully bridge the gap between the plates 1, above the coupling devices, at the same time keeping the meeting edges of the plates 2 in close contact with each other while the cars are running and thus prevent any substantial separation at any time of said edges when the cars are intercoupled, which separation might sometimes be caused by oscillation of the parts and uneven strain on the couplers.

Under each of these connecting plates 2 is a transverse angle beam located crosswise of the car platform, which beam has a vertical member 4 and a horizontal or flange member 3, the latter member 3 being secured in a suitable manner to the underside of the corresponding plate 2; and the vertical side 4

being secured to a parallel plate or bar member 8, which belongs to the lower end of the vestibule frame, it being noted that the outer edge of plate 2 rests upon or is firmly connected to the top edge of said plate 8, as seen in Figures 2 and 3. Thus each car platform has the same carrying means for its movable plate 2, said means consisting of the angle beam 4, 3, and the vestibule frame plate 8, which are united together and to the plate 2 into a single unit after the manner described or in some equivalent way. And thus there are two such units in a closely contiguous relation when two cars are coupled together, causing an arrangement such that the lower sections 8 of the two vestibule frames are in close contact with each other at the same time that the remaining upright front faces of said frames are closely associated as seen in Figure 2.

These vertical vestibule frames are only partially shown so far as may be necessary, but they appear in elevation in Figure 3 and in edge view in Figure 2. So far as my present invention is concerned it is enough to illustrate the parts I have shown, and to say that the two frames, one on each platform, are rectangular and closely adjacent to each other when the cars are coupled together. Each frame has the vertical flat side strips 7, 7, connected at the top by the integral cross strip 7^a, and at the bottom ends by the horizontal cross strip or plate 8. These latter plates 8 are riveted or secured to the angle beams 4 by rivets or bolts 17. Hence the lower ends of these vertical frames are united with the units above spoken of so as to be included together with the platform plates 2 and the angle beams 4, 3; so that the upright 7 and the rectangular frames of which they are a part, the plates 2 and the angle beam are so joined together as to have a unitary movement, and since they are located on each car platform it will follow that as the vestibules of two cars are brought into close association the plates 2 will have their transverse edges brought into contact, and during the fluctuations and vibrations of the various parts the plates 2 will move more or less towards or away from each other or sidewise carrying the various connected elements with them.

It may be remarked that these frames having the members 7 and 8 are obviously only the outer frames of the vestibules. They are connected usually by accordion or bellows-like expansion parts with similar upright frames 32, which are the main stationary uprights of the vestibule construction, but the details of these expansion members are not shown, except in dotted lines, as they are not necessary to the present explanation.

The chief problem which my invention seeks to solve therefore is the provision of means for keeping the plates 2, 2, closely up

against the underside of the platform plates 1 during all the oscillations to which said plates 2 are subject as the car platforms vibrate and jar and strain under the load carried or the rapid or uneven speed and irregularities of the rails as well as roadbed defects. Therefore to solve the problem satisfactorily I arrange under these plates 2 resiliently-acting means constructed and applied in the following manner:

In a bearing below the car platform, which bearing may be formed as part of the main frame, or the transverse beam 25 is a longitudinal rod or bar 5 adapted to travel endwise, its forward end being connected to one of the angle beams which carry the plates 2 and associated parts so as to particularly control the position of said plate 2. The rear end of bar 5 is yieldingly connected to the main car frame, as 27, by means of a spring 6 which surrounds the inner end thereof and is tensioned between the angle piece 28 riveted to frame 27 and the aforesaid bearing for this bar 5; the end of the bar 5 that passes through part 28 being screw threaded at 30 and provided with a nut 29 so as to tighten or loosen the strain and regulate its power. There is a similar arrangement of a bar 5 on each car buffer so that when the vestibule frames meet each other in car coupling and the like, the plates 2 may be adjustable or movable back and forth as much as may be necessary under the yielding control of the spring connections as described. There will usually be two bars 5 in each car buffer, one on each side, so as to balance the strain and action on the plate 2, that is to say each plate 2 will be under the control of two of the spring-provided bars.

Further, the end of each bar 5 nearest the angle beam 4, 3, is formed with an eye at 11 that receives a vertical pin whose upper end 12 enters a round hole in the angle beam flange 3 and bears against plate 2, there being a spring 13 between the eye 11 and the flange 3; while the lower end 14 of the pin enters an opening in a short angle plate 9 that is riveted to the angle beam member 4 near its lower edge, as shown in Figure 5, a spring 15 being interposed between eye 11 and the angle plate 9 and surrounding pin section 14. Thus since the eye 11 is in line with the holes in the flange 3 and the plate 9 the parts can all be easily assembled by inserting the pin from below through the openings, at the same time positioning the springs 13 and 15 above and below the eye 11; and a plate 10 is then riveted to the underside of the angle plate 9 to hold the pin in position after it has been so inserted. By this means therefore a connection is made between the unit that includes the plate 2 and the control bar 5; and also the plate 2 and associated parts are carried resiliently on the bar 5 so as to enable said plate to be kept in close con-

5 tact with the platform plate 1 and also to enable the other parts which are associated in a unitary combination with the plate 2 to be kept in their proper relative position during the expansion and contraction of the bellows-like devices in the vestibules and during the fluctuating relations of the different parts that arise in consequence of uneven conditions of various kinds. When for any cause 10 the plate 2 is depressed more or less between its contact with plate 1, the spring arrangement just described will quickly restore its contact, noiselessly and without shock or undue vibration.

15 Since there are duplicate spring mechanisms between each plate 2, or any number of such mechanisms corresponding to the number of the control bars 5 it will be evident that the even action of the buffer mechanism on 20 both of the abutting platforms is regulated and insured, and the bridge consisting of the two plates 2 between the two car platforms is preserved at a proper level and is capable at all times to allow easy passage by the passengers from one car to the other under all 25 conditions of speed and vibratory movements, the platforms being therefore as safe and as protective for the passengers as the interior of the car itself.

30 In order that the contact between the front frames of the vestibule structures at the meeting ends of two cars may be properly maintained and easily made when the cars are intercoupled and that this may be without 35 shock or clash as the cars rock and the couplings oscillate and adjust themselves, I find it convenient to provide the meeting faces of the upright sides 7 of these frames, as well as the bottom connections 8 with suitable ball 40 bearings. An example of such ball bearing is shown in section in Figure 4. Here the single ball A protrudes slightly through an opening in the strip 7, projecting enough to allow it to roll on the surface of the adjacent 45 strip 7 of the frame on the other car, as shown clearly in Figure 2. The ball A is kept in place by a series of small balls 23 surrounding it and carried in a raceway 22 that is enclosed in a box 21, whose flanges 24 are 50 screwed or riveted to the plate 7 on the rear side of the same, or the side opposite to that on which the ball A projects to meet the adjoining strip 7. Each of these vertical frames having members 7 and 8, which meet on the 55 two cars, have two of the balls A, one in each member 7, and with two such ball bearings in each connection 8, but the two balls in one frame are staggered in their relation to each other.

60 This staggered position of the balls in the two frames causes the balls in one frame to contact at different points from the balls in the other frame. Each frame therefore carries two or more such ball bearings which 65 project through the frame and roll upon the

face of the adjoining frame. And this is found to be far preferable to having one frame provided with a number of ball bearings and the other frame with no such ball bearings, for it prevents the possibility of 70 the meeting of two vestibules having no ball bearings, or two vestibules both having ball bearings in the same position which would cause a clashing of action. In the case of the connections 8, as seen in Figures 2 and 5, the 75 balls A lie not only in openings in the plate 8 but also in coinciding openings in the member 4 of the angle beams, and this latter member 4 carries its ball bearing in a box 31 riveted to the rear side of the member 4 as indicated in Figure 5. Obviously I am not confined to this special arrangement but can modify and change the same at will provided only the meeting faces are provided with 80 protruding spherical segments of balls to roll 85 on each other and cause ease and smoothness of operation.

Also the member 4 has riveted thereto centrally a small wearing plate 16 against which bears a ball B of a ball bearing supported 90 in the end of a buffer center stem 18 intermediate between the two bars 5 that belong to each plate 2, said stems 18 being carried by spring-actuated frames, whose springs 20 are supported in frames 19 under the platforms of the cars, and these ball bearing stems 18 assist the bars 5 in holding the combined mechanism at the front end of the platform in proper yielding relationship as already set forth. It will further be noted 100 that the movement of the bars 5 is assisted by ball bearings 26 arranged on the castings that carry the bars 5 as already explained.

The ball bearing 26 which are arranged in the end sills 25 beneath the platforms 34 and 105 in connection with the spring-provided bars or rods 5 are shown in additional details in Figure 7 so as to bring out more clearly and fully the way in which these balls belonging to the ball bearing apply their rolling effect to the longitudinally or endwise movable bars or rods 5 in order that the latter may have a noiseless and easy reciprocation in the operation of the buffer mechanism which I am now describing as constituting 110 the essential mechanism of my present improvements. The numeral 26 applies specifically to the casing or raceway that is carried in the sill 25. Said casing 26 contains one or two or more circular series of balls 40, 115 which are preferably separated slightly by cages, wires, or similar divisional means for slightly separating the series of balls and keeping them in proper position to roll easily and to be aligned properly with respect to each other, and in order that the rolling effect of the balls 40 on the shaft 5 as the latter reciprocates may be simple, easy and effective. Preferably I employ two circular series of balls 40 properly spaced apart by 120 125 130

means of the intervening cages or wire holders 41, and these balls 40 have plenty of play within the raceway or casing 26, while the rod 5 moves back and forth, thus rendering the movement of the rod and the platform mechanism noiseless and easy.

What I claim is:

In car buffer mechanism of the class described, the combination with a car platform, 20 of a vestibule frame therefor, an auxiliary plate beneath the platform and supporting the vestibule frame, an angle plate beneath the aforesaid plate and secured to said plate and to the vestibule frame in a unitary combination, a horizontal buffer stem supported beneath the platform, a pin loose in the end of said stem and beneath the angle plate in an opening of which the upper end of the pin is held, an angle piece secured on the 25 lower edge of the angle plate to which the lower end of the pin is secured in order to be rigidly carried thereby, springs surrounding the pin above and below the stem and tensioned between the stem and the upper flange 30 of the angle beam and the angle piece on the lower edge of the angle plate, said springs being arranged so as to resiliently and adjustably hold the plate in contact with the under-side of the platform.

30 In testimony whereof I hereunto affix my signature.

JOSEPH L. ORTNER.
